UNITED STATES PATENT OFFICE.

JOHNNY G. C. AKERS, OF WALLACE, NEBRASKA.

AMUSEMENT DEVICE.

Application filed September 11, 1926. Serial No. 134,854.

This invention relates to an amusement device of the type generally known as a carousel or merry-go-round, and contemplates a structure primarily intended for use by children, the invention residing in the construction, combination and arrangement of parts as claimed.

In the drawings forming part of this application like numerals of reference indicate similar parts in the several views and wherein:

Figure 1 is a top plan view.

Figure 2 is a sectional view on line 2—2 of Figure 1.

Figure 3 is a sectional view on line 3—3 of Figure 2.

Figure 4 is a sectional view on line 4—4 of Figure 2.

Figure 5 is a view of one form of brake.

Figure 6 is a view of another type of brake.

Referring to the drawings in detail 10 indicates the base of the amusement device adapted to repose upon the ground, and held 25 fixed thereto by means of stakes 11 driven into the ground, and attached to the base by chains 12. Arranged centrally of the base is a pedestal 13 upon which is mounted the axle or pivot 14. The lower end of this axle 30 or pivot 14 is formed to provide an annular chamber 15 for the reception of suitable ball bearings 16, upon which the hub 17 reposes as clearly illustrated in Figure 2. The annular chamber 15 is also adapted to contain 35 lubricant for the ball bearings 16. The axle or pivot 14 is secured to the pedestal 13 by fastening elements 18, which are also utilized to secure the upper ends of braces 19 to the pedestal, the corresponding lower 40 ends of these braces being secured to the base 10 as shown.

Radiating from the hub 17 is a plurality of tubular bars 20, preferably gas pipes of suitable lengths, and these bars 20 have their 45 corresponding inner ends secured in any suitable manner to the annular flange 21 forming part of the hub 17. The bars 20 of course are horizontally disposed and are connected by rods 21' at appropriate points 50 between the ends of said bars, and as clearly illustrated in Figure 4, the ends of the adjacent rods 21' are curved over the adjacent bar 20, and these ends 22 of said rods are connected together by a bolt or the like indicated at 23.

The bars 20 constitute part of a seat sup-

porting frame, which also includes a plurality of tubular bars 24 which have their corresponding inner extremities secured to an annular flange 25 arranged adjacent the 60 upper end of the hub 17. It will be noted that each of the bars 20 extend outwardly and downwardly and have their outer extremities arranged horizontally directly above the adjacent bars 20. Interposed between each bar 20 and the adjacent bar 24 is a strap 26 including a curved intermediate portion straddling the bar 20, and secured to the latter and also to the adjacent end of the bar 24 by means of a bolt 27. 70 The extremities of the strap 26 project laterally at the opposite sides of each bar 20, and have supported thereon the adjacent end of a seat 28, the seats being secured to the straps 26 by bolts or the like 29. The 75 bars 24 also consist of suitable lengths of piping, and are connected together and braced by the rods 30, the ends of the adjacent rods being curved about each bar 24 as indicated at 31, and these curved extremities are connected together by bolts or other 80 suitable fastening means in the same manner as the extremities of the rods 21 above mentioned and illustrated in Figure 4.

In Figure 5 I have illustrated a brake for 85 the device, which includes a brake band 32, one end of which is fixed, and the other end of which is connected with a link 33 pivoted as at 34. The free end of this link is connected with a hand operated lever 35 by 90 means of a connecting element 36, so that when the lever 35 is moved upon its fulcrum in one direction, the brake band 32 is contracted to stop the device.

In Figure 6 I have shown a modified construction, wherein the brake band 37 has its free end connected with a lever 38 which is pivoted at 39. This lever supports a weight 40 which is adjustably mounted upon the lever 38 and adapted to be held fixed relatively 100 thereto by means of a suitable pin 41 passed through the weight and one of the openings 42 of the lever. In this form of the invention the lever 38 is swung to an active position by the centrifugal force when the device 105 rotates above a predetermined speed, thereby automatically retarding the rotation of the device as will be readily understood. The speed at which the lever 38 is swung to an active position, is of course regulated by the 110 adjustment of the weight 40 along different parts of the lever.

It will be manifest that I have devised an amusement device of the class in question, especially adapted for use by children, who occupy the seats 28, and if it be desired use 5 may be made of the rods 30 in the capacity of handle bars to be grasped by the occupants of the adjacent seats. Of course the amusement device may be rotated by any suitable means, the general construction and 10 arrangement of parts affording the device the desired strength and rigidity.

While it is believed that from the foregoing description, the nature and advantages of the invention will be readily apparent, I 15 desire to have it understood, that I do not limit myself to what is herein shown and described and that such changes may be resorted to when desired as fall within the scope of what is claimed.

20 What is claimed is:

An amusement device of the character described, comprising a base, a pedestal ar-

ranged centrally thereon, a pivot rising from said pedestal, and including an annular chamber surrounding the pivot immediately 25 adjacent said pedestal, a hub rotatably mounted on the pivot and received by said chamber, ball bearings interposed between the lower end of the hub and the bottom of said chamber, a seat supporting frame like 30 structure including a plurality of radially disposed bars carried by said hub, a split brake band surrounding said hub and having one end fixed to the adjacent bar of said frame, a lever pivoted on said bar, the other 35 end of said brake band being secured to said lever at an appropriate point in its length, and a weight adjustably mounted on the lever and adapted to be positioned to automatically move the lever by centrifugal force 40 to apply the brake at a predetermined speed of said frame.

In testimony whereof I affix my signature,

JOHNNY G. C. AKERS.
